UNITED STATES PATENT OFFICE.

JAMES P. HOOPER, OF RUXTON, MARYLAND, ASSIGNOR TO WILLIAM E. HOOPER & SONS COMPANY, OF BALTIMORE, MARYLAND, A CORPORATION OF MARYLAND.

PACKAGE.

Application filed March 23, 1927. Serial No. 177,574.

The invention relates to the wrapping of cylindrical packages and has been developed and practiced principally in connection with the wrapping or packaging of cylindrical

5 bolts or rolls of textile and other fabric.

Such rolls or bolts of fabric are, in accordance with the present practice, protected by wrapping with sheet material, as paper passed about the cylindrical surface of the

10 same as the fabric itself is wrapped in rolling. The ends of the bolt, if protected at all, were covered with considerable difficulty. Further, the bolts when so wrapped, in accordance with previous methods, as to en-

15 close the ends as well as the sides, could not be mounted on a shaft or pole thrust through the center of the roll in accordance with the practice of mounting such bolts for use, as the wrapping completely closed the axial

20 ends, and to mount the bolt in this manner it was necessary to remove the wrapping.

The present invention relates to a method 25 of wrapping cylindrical bolts of fabric and sheet material which may be performed mechanically as well as by hand, and to a cylindrical package so wrapped, and other bodies capable of similar treatment.

The article embodying the invention consists of a cylindrical body which may be a 30 roll or bolt of sheet material, as fabric wrapped with a narrow continuous strip of sheet wrapping material, as paper or water proof paper, cloth or the like, wound about the cylindrical body, the strip fabric being

35 placed on the cylinder in the form of a series of loops, each loop being passed about the cylinder substantially in the direction of the intersection with the surface thereof or the line formed by the intersection of

40 the surface thereof with a plane parallel to the axis of the cylinder, but preferably spaced slightly away from said axis. The spacing is not essential unless it is desired to leave the ends open at the centers. The

45 successive loops are placed on the cylindrical surface edge to edge, or slightly overlapping, and passed across the ends parallel to the different diameters thereof, the angle of each loop being varied from the angle

50 of the next preceding loop to provide for the laying of the successive loops edge to edge

or slightly overlapping, as aforesaid. The method thus outlined in connection with the description of the package is a feature of

55

In the accompanying drawings I have illustrated a package embodying my invention in the preferred form and illustrating the method of the invention.

In the drawings:

Figure 1 is a perspective view of the finished package in accordance with the invention.

Figure 2 is a similar view of the package 60 partially wrapped.

Figure 3 is a perspective view of a fragment of paper strip which is particularly adapted to use as a wrapping material for such packages, the different layers being broken away for convenience of illustration.

Figure 4 is a cross section on an enlarged scale on the line 4—4 of Figure 3 showing the same wrapping strip.

Figure 5 is a fragmentary view illustrating the use of two strips side by side in 75 wrapping the roll.

Referring to the drawings by numerals, each of which is used to indicate the same or similar parts in the different figures, the package, as shown, comprises a cylindrical body 1 which, in accordance with the preferred form of the invention as practiced, is a cylindrical bolt or roll of sheet material, as textile fabric 2. This cylindrical body 1 is wrapped or covered, in accordance with 80 the invention, by placing the end of the strip on the cylinder, preferably on the end as at 13 and then winding one or more narrow strips of sheet material 3, which is preferably paper, about the cylinder forming a series of loops, each loop being laid substantially on the line formed by the intersection with the surface of the cylinder, of a plane parallel to, but preferably spaced 85 slightly away from the axis of the cylinder.

95 It will be noted that the separate loops 4 in which the wrapping strip is laid on the cylinder 1 overlap slightly at 5. The angle of the respective loops, as shown at the end of the cylinder 6, is changed with 100 each loop or successive single turn of the material about the package. The angle between

the respective adjacent successive loops or turns 4 is shown as equal to the angle between two radii which are spaced at the periphery of the package by an arc of a length substantially equal to the width of the strip 3 reduced by the overlap 5 of the edges on the cylindrical surface.

The spacing of the strip 3, or more particularly the portions 7 of each loop which cross the ends of the cylinder, away from the center, produces the central openings 8 in the wrapper at the ends which may be utilized for insertion of a pole or shaft on which the bolt of cloth may be mounted for unwrapping, the wrapping being retained to protect the bolt until it is used, but the spacing of the loops and particularly the portions 7 thereof crossing the ends away from the center, as described, is not essential to the practice of the invention. The outside end of the strip 3 at 16 may be fastened in any suitable manner, as by means of adhesive.

In Figures 3 and 4 I have shown a strip of water proof paper which has been found satisfactory and desirable as a wrapping means for the package of the invention, producing a substantially waterproof package. The material thus illustrated is a laminated material consisting of two strips 10 of paper or the like, each of which is coated on one side with a sticky asphalt compound, the coating being indicated by reference character 11. On this is laid a coating of cheap fiber 12, as hemp, jute, or the like, there being preferably a layer of this material on each of the layers of sticky material 11. The fibers are preferably deposited in two layers 14 and 15 at right angles to each other. The strips of paper 10 thus coated on one side with the sticky asphaltic material 11, and the fibers 12 preferably laid at right angles, as shown at 14 and 15, are placed with the coated sides in contact and rolled to press the asphalt through the fibers and cause the two strips to adhere closely. This material may be manufactured in the form of endless or long webs of considerable width and cut into strips for the purposes of the present invention. The practice of the invention is not intended to be limited to the use of any particular material in and for the wrapping strips.

The package and method thus described have considerable advantages in that the rolls may be quickly wrapped in this way by machinery, dispensing with a large part of the former expense for labor which must be somewhat skilled to perform the formerly practiced wrapping operation by hand.

The packages thus wrapped are further completely protected, as the wrapping closely overlies the material being wrapped and is not easily displaced and, as aforesaid, the wrapping may be so applied without diffi-

culty as to leave the axial aperture 9 in the roll open at 8 for the admission of a shaft or pole on which the roll or bolt is mounted for use of the material, the wrapping being thus permitted to remain in place, protecting the material until it is used.

By use of the waterproof wrapping strip described, a waterproof protecting cover is instantaneously applied to the bolt.

I have thus described specifically and in detail a method and article in accordance with my invention in order that the nature and manner of practicing the invention may be clearly understood. However, the specific terms herein are used descriptively rather than in a limiting sense, the scope of the invention being defined in the claims.

What I claim as new and desire to secure by Letters Patent is:

1. A package comprising a cylindrical body and a wrapping therefor in the form of strip material extending around the package in a series of loops, each loop encompassing the entire outside surface of the package and lying thereon in a line which is substantially the intersection with the cylindrical surface of a plane parallel to the axis, and each loop being at an angle to the succeeding loop whereby the wrapping material is caused to contact as to the edge portions and cover the sides and ends of the cylinder.

2. A package comprising a cylindrical body and a wrapping therefor in the form of strip material extending around the package in a series of loops, each loop lying thereon in a line which is determined by the intersection with the cylindrical surface of a plane parallel to the axis, each loop encompassing the entire outside surface of the package and being at an angle to the succeeding loop whereby the wrapping material is placed in contact as to the edge portions of the adjacent loops and uniformly distributed over the sides of the cylinder, the loops being spaced slightly from the center to leave an opening at the center of each end.

3. A package comprising a roll of fabric and a covering for the same comprising a narrow strip of paper, and asphaltic material and fiber covered by the paper strips, the wrapping material being placed on the roll in the form of a series of overlapping loops each loop encompassing the entire outside surface of the package and crossing the curved sides of the roll in a direction parallel to the axis and crossing the ends, the angle of each loop being different from the angle of the preceding loop, so that the material covers the entire surface of the package and is uniformly distributed over the curved sides of the roll.

4. A package comprising a body and a covering for the same in the form of narrow

strip material, the wrapping material being placed on the body in the form of a series of overlapping loops, each loop encompassing the entire outside surface of the pack-

age and crossing the sides of the body in a direction parallel to the axis and crossing the ends, the angle of each loop being differ-

ent from the angle of the preceding loop, so that the material covers the entire surface of the package and is uniformly distributed ¹⁰ over the sides of the body.

Signed by me at Baltimore, Maryland,
this 17th day of March, 1927.

JAMES P. HOOPER.
